UNITED STATES PATENT OFFICE.

CHARLES R. BEEBE, OF NEW HAVEN, CONNECTICUT.

ELECTRIC SWITCH.

No. 922,746.

Specification of Letters Patent. Patented May 25, 1909.

Application filed January 11, 1909. Serial No. 471,741.

To all whom it may concern:

Be it known that I, CHARLES R. BEEBE, a citizen of the United States, residing at New Haven, in the county of New Haven 5 and State of Connecticut, have invented a new and useful Improvement in Electric Switches; and I do hereby declare the following, when taken in connection with the accompanying drawings and the letters of reference marked thereon, to be a full, clear, and exact description of the same, and which said drawings constitute part of this specification, and represent, in—

Figure 1 a perspective view of a switch box 15 constructed in accordance with my invention. Fig. 2 a plan view of the inside of the box with the cover removed. Fig. 3 a vertical sectional view through the box. Fig. 4 a side view of the key detached.

20 This invention relates to an improvement in electric switches, and particularly for motors for boats and vehicles.

In starting motors it is customary to turn the switch to the battery for preliminary 25 sparking, and then when the motor is running it is switched to the magneto. It is also desirable at times to remove the switch key so that the motor cannot be tampered with.

The object of this invention is a simple arrangement of switch mechanism which is 30 positive in action and from which the key may be readily removed, and when removed positively cuts out the sparking mechanism; and the invention consists in the construction hereinafter described and particularly recited in the claims.

The switch box 2 may be of any desired 40 form, preferably round, and formed from fibrous or other insulating material. This cover has a backing 3 also of fiber or other material on which the parts are mounted. These consist of contact posts 4, 5 and 6 to which wires are suitably connected, the connection 5 leading to the magneto, and the 45 connection 6 to the battery. Mounted on the back is a switch arm 7 provided with an outwardly extending angular lug 8. Secured to the post 4 is an arm 9 formed at its outer end with a collar 10 which sets over the 50 lug 8 and is held out of contact with the arm 7 by an insulating washer 11. The cover 2 is formed with a bushing 12 which provides a bearing for a key 13 bifurcated at its inner

end to set over the lug 8 and contact therewith, and of a diameter to closely fit the 55 collar 10, the key being provided with a suitable knob or handle 14 by which it may be rotated. When the key is inserted it connects the arm 9 with the arm 7 and provides means for turning the arm 7 from the intermediate position to a contact plate 15 connected with the post 5, or a contact plate 16 connected with the post 6 and so that connection is made either through a battery or through the magneto according to the direction in which the key is turned. The key 65 may be removed from either position, and when removed immediately breaks contact. I thus provide very simple switch mechanism which is positive in its action and which by 70 removal of the key breaks the circuit.

I claim:—

1. An electric switch comprising a box, a switch arm mounted therein, contact plates over which the switch arm may be turned, 75 said switch arm formed with an outwardly projecting lug, an arm mounted in the box and formed at its outer end with a collar adapted to surround said lug, combined with a bifurcated key adapted to engage with said lug and of a diameter to contact with said ring, substantially as described.

2. An electric switch comprising a cover, a back, three posts mounted in said back, contact plates connected with two of said posts, 85 a contact arm mounted in said case and adapted to be turned from one contact plate to the other contact plate, the said arm formed with an outwardly projecting lug, an arm secured to the other contact post and 90 formed at its end with a collar adapted to surround said lug, combined with a key adapted to be inserted through said cover, said key bifurcated at its inner end to engage with said lug and of a diameter adapted to 95 enter said collar whereby said lug and collar are electrically connected; substantially as described.

In testimony whereof, I have signed this specification in the presence of two subscribing 100 witnesses.

CHARLES R. BEEBE.
